ALBERT S. FALCONER, OF LOS ANGELES, CALIFORNIA, ASSIGNOR OF ONE-HALF TO
FRANCES L. BROZMER, OF LOS ANGELES, CALIFORNIA.

DISAPPEARING WINDOW.

1,125,992.

Specification of Letters Patent. Patented Jan. 26, 1915.

Application filed September 22, 1913. Serial No. 791,205.

To all whom it may concern:

Be it known that I, ALBERT SHELLY FALCONER, a citizen of the United States, residing at Los Angeles, in the county of Los Angeles, State of California, have invented new and useful Improvements in Disappearing Windows, of which the following is a specification.

This invention relates to disappearing windows of the general type where the sash is adapted to be moved into a pocket adjacent the window opening, and relates particularly to such a window where the sash is movable vertically into a pocket preferably below the window opening. And the invention consists primarily in a certain combination of the movable sash with a movable table adapted to support the sash.

In its preferred form, my invention includes in its combination a means whereby the movable table is moved positively by virtue of the movement of the sash; and preferably the table is placed to support the sash in its normal position in the window opening. I use a co-operating mechanism on the table and sash whereby when the sash is raised to a certain pre-determined height the table is moved in under the sash to support it, and whereby when the sash is moved to another certain pre-determined height the table is moved out from under the sash so as to allow the sash to drop into the pocket below the window opening.

It is an object of this my invention to provide mechanical means for effecting the above outlined operation in simple and inexpensive and practicable form; and my preferred mechanical means are shown in the accompanying drawings in which,

Figure 1 is a vertical central section showing my invention as it appears in use. Fig. 2 is an exterior elevation with parts broken away, Fig. 3 is a detailed enlargement of a portion of Fig. 1, Fig. 4 is a fragmentary section taken on line 4-4 of Fig. 3, Fig. 5 is a perspective showing the co-operating parts which effect the movement of the table by virtue of the movement of the sash.

In the drawings the numeral 10 may designate generally the wall of a dwelling or any other structure and 11 may designate a window frame therein. This window frame has the usual window opening and has a pocket 12 below that opening. At the side of the framing there are vertical guides 13

and these guides extend alongside the window opening and down into the pocket 12. There may be also another pocket placed above the window opening and the guide 13 may extend upwardly into this pocket also. 60 This pocket is designed to hold a screen 14, the construction of which and its combination with the window are the subject matter of a co-pending application for U. S. Letters Patent. It suffices for the purpose of 65 this present application to explain that the window sash 15 slides vertically in the guides 13 between its upper position in the window opening and its lower position in the pocket 12. Suitable handles 16 are provided for manually causing the vertical movement of the sash; and the weight of the sash may be balanced by a suitable balance means which I have indicated in the drawings of this application and which is the 75 subject matter of another co-pending application for U. S. Letters Patent. Herein it will suffice to explain that I prefer to mount a balance box 20 below the sash 15 and extending from side to side of the window 80 opening. Rotating drums 21 are mounted in the box and sheaves 23 are placed at the ends. Flexible members 22 extend from drums 21 and over sheaves 23 and are attached at their ends 24 to the window 85 frame; so that the winding up of the drums 21 will tend to raise the sash and balance it so that it may be easily moved up or down.

On the stationary table 30 I mount my 90 movable table 31, the movable table extending from side to side of the window opening and being of substantially the same width as the sash itself. My movable table is preferably constructed with the cross sectional configuration shown best in Figs. 3 and 5 having an outer overhanging portion 31^a which, when the table is in the position shown in Fig. 3, strikes up against a stop 32 which may be made integrally with the 95 stationary table itself. When the table 31 is in the position shown Fig. 5 its portion 31^a strikes the stops 32 which limit its outward movement. Stationary table 30 is on the ordinary angle of inclination; and I 100 prefer to place my movable table 31 at the same angle so as to facilitate the shedding of any water which may gain entrance around the edges of the sash. Consequently the movement of my movable table is not 11

exactly horizontal, the movement being inwardly and slightly upwardly or opposite.

At the end of the movable table is carried a bracket 40 on which an inwardly projecting pin 41 is mounted. This bracket 40 has an upwardly projecting rib 43 adapted to engage in a longitudinal groove 43 on the bottom edge of the sash, the engagement of this rib in the groove preventing the outward movement of the table when the sash is in position as shown in Fig. 3. With the table in the position of Fig. 3 the pins 41 are approximately in the position shown in that figure, the pins being at each end of the sash and directly beneath it. When the pins 41 are in the position shown in Figs. 5 the sash 15 may be lowered, the pins 41 passing through grooves 45 on the lateral edges of the sash.

At its bottom and on each side of the sash 15 is carried a bracket 50 having inclined plane members adapted to coöperate with the pins 41. At the lower ends of each bracket 50 there is an inclined plane 51 set in such a position that its engagement with the pins 41 by movement of the sash 15 upwardly will cause the pins and the table 31 to move in the direction indicated by the arrows. Above the inclined plane surface 51 there is an inclined block 52 pivoted at 53 and having a spring 54 which tends to throw it toward and hold it in the position shown in Fig. 5. The lower pivoted end of the block 52 is approximately over the central portion of the inclined plane 51, while the lower end of the inclined plane 51 is approximately beneath the central portion of the block 52.

When the parts are in their relative positions shown in Fig. 5, the sash 15 may be lowered into the pocket 12; and the depth of the pocket is usually such that the sash is carried down until its upper edge is flush with the table of the window opening.

A handle on the top of the sash may provide means for starting its upward movement. The sash may be moved upwardly to a position considerably above the position shown in Figs. 3 and 4. On its upward movement, the inclined plane 51 will engage the pins 41 at each side of the sash and this operation will cause the movable table 31 to be moved from the position shown in Fig. 5 to the position shown in Fig. 3. The pins 41 will then be below the central portions of the inclined blocks 52 and on lowering the sash onto the table 31 the pins will engage with the inclined blocks 52 and cause those blocks to be straightened into vertical positions, without moving the pins 41 farther inwardly, as the table 31 has moved up against the stop 32. Thus, the sash may be set down upon the table 31; the ribs 42 entering the groove 43 so as to prevent reverse move-

ment of the table until the sash is raised. In order to move the table outwardly so that the sash may be lowered, it is necessary to raise the sash so that the upper inclined faces of inclined blocks 52 may engage the pins 41 to move them into the position shown in Fig. 5. But the sash is not moved upwardly enough to engage the inclined planes 51 with the pins 41, for if this were done the table would be moved inwardly again. When the table has been moved outwardly by raising the sash to the lesser height the sash may be lowered into the pocket.

It is seen that my window is simple in both construction and operation. Its operation involves two simple movements as described; and when the sash is in normal closed position all the parts are interlocked and held securely in proper relation. To the fundamental features of construction I direct the following claims; the details described, although composing my now preferred form of device, may be varied without departing the spirit of my invention.

I claim—

1. In combination, a vertically movable sash or the like, a horizontally movable table at the lower edge of the sash, and coöperating means on the sash and table causing movement of the table in one direction when the sash is raised to a certain height above the table and causing movement in the opposite direction when the sash is raised to a greater height.

2. In combination, a window frame including an upper window opening and a window receiving pocket below, a horizontally movable table mounted on the frame at the lower end of the window opening, a sash vertically movable between the opening and the pocket, the sash normally resting upon the table in the window opening, and coöperating means on the sash and table causing horizontal movement of the table when the sash is lifted off the table and moved vertically thereabove.

3. In combination, a window frame including an upper window opening and a window receiving pocket below, a horizontally movable table mounted on the frame at the lower end of the window opening, a sash vertically movable between the opening and the pocket, the sash normally resting upon the table in the window opening, and coöperating means on the sash and table causing horizontal movement of the table in one direction when the sash is lifted off the table to a certain height and causing horizontal movement in the opposite direction when the sash is lifted above that certain height.

4. In combination, a window frame including an upper window opening and a sash receiving pocket below, a horizontally

movable table mounted on the frame at the lower end of the window opening, a sash vertically movable between the opening and the pocket, the sash normally resting upon the table in the window opening, pins carried by the table, and inclined planes carried by the sash normally below the pins and adapted to engage the said pins to move the table horizontally when the sash is raised off the table.

5. In combination, a window frame including an upper window opening and a sash receiving pocket below, a horizontally movable table mounted on the frame at the lower end of the window opening, sash vertically movable between the opening and the pocket, the sash normally resting upon the table in the window opening, and co-operating means on the sash and table causing horizontal movement of the table in one direction when the sash is lifted off the table to a certain height and causing horizontal movement in the opposite direction when the sash is lifted above that certain height, said means including inclined planes carried by the sash normally below the table and adapted to engage the said co-operating means on the table when the sash is lifted off the table.

30 6. In a device of the character described a vertically and a horizontally movable member, a pin on the horizontally movable member and a pair of inclined planes on the vertically movable member each adapted to engage said pin, said planes being inclined in opposite directions and one arranged above the other, the lower end of the upper plane being located medially over the lower plane.

40 7. In a device of the character described, a vertically and a horizontally movable member, a pin on the horizontally movable member, an upwardly facing inclined plane on the vertically movable member, an inclined plane block pivoted at one end on said vertically movable member at a point above the central portion of the said inclined plane, and spring means to hold said block at an inclination opposite to that of said plane.

50 8. In combination, a vertically movable member or the like, a horizontally movable sash supporting table adapted to move into the path of the sash, co-operating means on the sash and table whereby the table is positively moved by movement of the sash above the position in which it is supported by the table, and interlocking means on the table and sash to prevent movement of the table while the window is supported thereby.

60 9. In combination, a vertically movable member or the like, a horizontally movable

sash supporting table adapted to move into and out of the path of the sash, co-operating means on the sash and table whereby the table is moved by movement of the sash above the position in which it is supported by the table, and interlocking means on the table and window to prevent movement of the table while the window is supported thereby, said interlocking means including a vertically projecting rib on the table and a groove in the window adapted to receive the rib.

75 10. In combination, a window frame and a window sash vertically movable therein, a sash supporting table horizontally movable into and out of the path of the sash, the sash normally being supported on the table, and co-operating means on the sash and table causing horizontal movement of the table out of the path of the sash when the sash is lifted off the table and moved vertically there-above.

85 11. In combination, a window frame and a window sash vertically movable therein, a sash supporting table horizontally movable to and from the sash, the sash being normally supported by the table, and co-operating means on the sash and table positively causing horizontal movement of the table away from the sash when the sash is lifted above its said normal position.

95 12. In combination, a window frame and a window sash vertically movable therein, a sash supporting member horizontally movable to and from a position in which it supports the sash, and co-operating means on the sash and supporting member for positively moving the member away from its said sash supporting position when the sash is moved upward from its position supported on the member.

105 13. In combination, a window frame and a window sash vertically movable therein, a sash supporting member horizontally movable to and from a position in which it supports the sash, and co-operating means on the sash and supporting member for moving the member away from its said sash supporting position when the sash is moved upward from its position supported on the member to a certain pre-determined height above its said supported position, and for moving the member to its said position for supporting the sash when the sash is moved to another certain pre-determined height above its said supported position.

115 14. In witness that I claim the foregoing I have hereunto subscribed my name.
